UNITED STATES PATENT OFFICE.

PINCUS FARB, OF NEWARK, NEW JERSEY, ASSIGNOR TO SONORA PHONOGRAPH CORPORATION, A CORPORATION OF NEW YORK.

TALKING-MACHINE CABINET.

1,321,194.

Specification of Letters Patent. Patented Nov. 11, 1919.

Application filed February 1, 1917. Serial No. 145,945.

To all whom it may concern:

Be it known that I, PINCUS FARB, a citizen of the United States, and a resident of the city of Newark, county of Essex, and 5 State of New Jersey, have invented a certain new and useful Improvement in Talking-Machine Cabinets, of which the following is a specification.

My invention relates to talking machine 10 cabinets, and more particularly to devices for securing the covers of such devices in the open position.

The object of my invention is to provide means whereby, when the cover is raised, it 15 will be securely retained in such position, and by which the cover may be moved to its closed position by the use of one hand only.

A further object is to provide means whereby the cover may be locked in open 20 position automatically, and to prevent undue strains on the securing means when the cover is being opened.

These and further objects will more fully appear in the following specification and accompanying drawings considered together 25 or separately.

I have illustrated my invention in the accompanying drawings, in which like parts are designated by the same reference characters in all of the figures, and in which,—

Figure 1 is a sectional view of a portion of a talking machine cabinet provided with my improvement, the cover being shown in the open position in full lines and closed in 35 dotted lines;

Fig. 2 is a section on the line 2—2 of Fig. 1 the supporting link being shown in elevation;

Fig. 3 is a detail horizontal section on the 40 line 3—3 of Fig. 1; and

Fig. 4 is a detail view of a modified form of supporting link.

In carrying out my invention, I provide a cabinet 1 having a motor board 2, to which 45 a motor (not shown) is secured. A top or cover 3 is hinged to the cabinet 1 above the motor board, and preferably at the back of the cabinet.

Secured to the inside of one side of the 50 cover, and in proximity to the top thereof, is a bracket 4 provided with a depending lug 5 to which is pivoted a link 6. The link is adapted to hang vertically when the cover is closed, and is so shaped or bent as to follow the lines of and lie in close relation to

the side of the cabinet and cover. The motor board is recessed or notched at 7 adjacent to the wall of the cabinet for the passage of the link, and a metallic lining or keeper 8 is disposed within the recess or notch. A 60 wear plate 9 is secured to the side of the cabinet in proximity to the keeper, and the link passes through the notch in the motor board between said keeper and wear plate.

The free end of the link is provided with 65 a bowed and preferably leaf spring 10 having its upper end riveted to the link and its lower end free and preferably resting upon the link and the extremity of the link below the spring is bent at right angles and 70 carries a resilient buffer 11. The buffer is spaced below the free extremity of the spring a distance slightly less than the thickness of the motor board. The combined 75 width of the link and the apex of the bowed spring is slightly greater than the passage in the motor board, so that the spring has to be compressed to effect its passage through the opening in the motor board.

The operation is as follows:

With the cover in the closed position as shown in dotted lines in Fig. 1, the front, that part opposite the hinges, of the cover is grasped by the hand, and the cover is raised and the link and its attached spring 80 drawn through the passage in the motor board and the spring compressed until it reaches the upper side of the notch. When the cover reaches its wide open position, the buffer will engage the bottom of the motor 85 board, and the movement will be arrested and the jar cushioned by the resiliency of the buffer. The spring will remain in frictional engagement with the keeper as it passes through the notch and press the link 90 against the wear plate, and such frictional engagement will support the cover in open position. When the cover has reached the limit of its open position, the lower curved 95 end of the spring in its expanded condition 100 will engage the upper edge of the notch and support the cover in open position.

It will not be necessary for the operator to exercise care as to the extent to which he raises the cover, but the cover may be raised 105 until it will travel no farther. The elastic buffer will prevent injury to the parts, and there will be no danger of the fastenings of the fitting 4 being pulled out.

When it is desired to close the cabinet, the 110

operator will grasp the front of the cover with one hand, and by exerting pressure enough to compress the spring 10, the cover may be closed. There are no locks to unfasten or to get out of order.

If desired, the link, as illustrated in Fig. 4, may be provided with a plurality of springs at intervals in the length of the link to provide for locking the cover in any one of several positions.

In accordance with the provisions of the patent statutes, I have described the principle of my invention together with the apparatus which I now consider to represent the best embodiment thereof, but I desire to have it understood that the apparatus shown is merely illustrative, and that the invention can be carried out in other ways.

Having now described my invention, what I claim and desire to secure by Letters Patent is:

1. A cabinet or other receptacle, a hinged cover therefor, a keeper on said cabinet, a link pivoted to said cover adapted to pass through said keeper, and a bowed spring fixed to and carried by said link and adapted to be drawn through from the under side of and engaged by the keeper and be compressed thereby, when the cover is raised, and to expand as it emerges from and engage the upper side of the keeper, to thereby support the cover in open position.

2. A cabinet or other receptacle, a hinged cover therefor, a keeper on said cabinet, a link pivoted to said cover adapted to pass through said keeper, a bowed spring fixed to and carried by said link and adapted to be drawn through from the under side of and engaged by the keeper and be compressed thereby, when the cover is raised, and to expand as it emerges from and engage the upper side of the keeper, to thereby support the cover in open position, and a resilient buffer on the lower end of said link to limit and cushion the upward movement of the cover and link.

3. A cabinet or other receptacle, a hinged cover therefor, a keeper on said cabinet, a link pivoted to said cover adapted to pass through said keeper, and a series of successive bowed springs fixed to and carried by said link and adapted to be drawn through from the under side of and successively engaged by the keeper and be compressed thereby, when the cover is raised, and to expand when emerging from and engage the upper side of the keeper, to thereby support the cover in different open positions.

This specification signed and witnessed this 17th day of January, 1917.

PINCUS FARB.
